US0D1097736S

(12) **United States Design Patent** (10) **Patent No.:** **US D1,097,736 S**
(45) **Date of Patent:** **** Oct. 14, 2025**

(54) **WEED TORCH**

(71) Applicant: **Pengyu Ji**, Shenzhen (CN)

(72) Inventor: **Pengyu Ji**, Shenzhen (CN)

(**) Term: **15 Years**

(21) Appl. No.: **29/992,456**

(22) Filed: **Mar. 7, 2025**

(51) **LOC (15) Cl.** **08-05**

(52) **U.S. Cl.**

USPC **D8/30**; D15/144

(58) **Field of Classification Search**

(57) **CLAIM**

The ornamental design for a weed torch, as shown and described.

DESCRIPTION

FIG. 1 is a perspective view of the weed torch showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view of thereof;

FIG. 8 is a bottom plan view of thereof;

FIG. 9 is an enlarged view of portion 9 in FIG. 1; and,

FIG. 10 is an enlarged view of portion 10 in FIG. 1.

The broken line portions are shown for illustration purposes and form no part of the claimed design.

1 Claim, 10 Drawing Sheets
